ATTORNEY:

UNITED STATES PATENT OFFICE

FREDERICK M. VENZIE, OF PHILADELPHIA, PENNSYLVANIA

BUILDING STRUCTURE

Application filed July 23, 1929. Serial No. 380,276.

This invention, generally stated, relates to a building construction and has more particular relation to a floor structure. It is common practice in building construction where I-beams are employed to leave the same exposed with the exception of a slight covering of cement, so that the contour of the ceiling is interrupted at intervals by these beams.

10 The leading object of the present invention is to overcome this disadvantageous feature and provide a structure in which the I-beams are entirely concealed between the floor surfaces and the ceiling surfaces.

15 A further object of the present invention is to provide a series of hollow tiles spaced between adjacent I-beams, each tile being of a height in excess of the height of an I-beam.

20 A further object of the present invention is to provide a cap for each hollow tile so that in the pour of the concrete none of it enters the hollow tiles.

25 A further object of the present invention is to provide a hollow tile of the character stated which is interiorly reinforced by ribs.

30 A further object of the present invention is to provide a tile of the character stated provided at its lower end with a flanged part having ribs upon two faces and grooves upon the other two faces so that adjacent tiles may interlock.

35 A still further object of the present invention is to provide a tile of the character stated the flanged part of which has upwardly projected therefrom a generally rectangular portion exteriorly provided with ribs so that a bond may be formed between the tiles and the concrete.

40 With these and other objects in view, the invention consists of the novel construction hereinafter described and finally claimed.

The nature, characteristic features and scope of the invention will be more fully understood from the following description taken in connection with the accompanying drawings forming part hereof, and in which:

45 Fig. 1, is a view in cross section of a floor and ceiling structure embodying the invention, taken upon the line 1—1 of Fig. 2.

Fig. 2, is a top sectional view taken upon the line 2—2 of Fig. 1.

Fig. 3, is a perspective view of one of the tiles.

Fig. 4, is a top or plan view of the tile 55 shown in Fig. 3.

For the purpose of illustrating my invention I have shown in the accompanying drawings one form thereof which is at present preferred by me since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

Referring to the drawings in detail, the reference numeral 1 designates an I-beam as used between a floor 2 and ceiling 3. In forming the structure after the I-beams are in place the usual scaffold or support, not shown in the drawings, is used to temporarily support the pour of concrete. Upon such temporary support between adjacent I-beams are positioned a plurality of tiles 4, best seen in Figs. 3 and 4, a detail description of which will hereinafter appear. These tiles are hollow and are arranged to receive at their tops 75 a plate or cover 5. When the tiles are positioned as shown in Figs. 1 and 2, a concrete fill 6 is introduced between adjacent tiles, as clearly shown in Figs. 1 and 2. The concrete fill may have introduced therein reinforcing 80 rods 7. With the concrete properly set the temporary scaffold is removed and a coating of ceiling plaster is added. By this arrangement and construction of parts it is noted that the I-beam is completely concealed from 85 view, and that the ceiling has a plane surface and is not interrupted by unsightly obstructions.

Taking up now specifically the construction of a tile, and referring more particularly to 95 Figs. 3 and 4, the reference numeral 8 designates a lower flanged portion, forming a solid base, which terminates in an upwardly extending hollow member 9. Two faces of the base 8 are provided with ribs 10 and the other 100

two faces are provided with channels 11. By this arrangement of parts the bases of adjacent tiles may have interlocked relation as clearly shown in Fig. 1, it being understood in this connection that wherever a beam 1 is present the meeting edges of a pair of adjacent tiles completely cover the bottom of the beam 1. The hollow member 9 of the tile is exteriorly provided with ribs 12 so that a bond may be formed between the concrete 6 and the tiles. The tiles are provided with reinforcing rods 13 at their tops and with reinforcing rods 14 in the base of the tiles, as best seen in Fig. 1. The tile is interiorly provided with a reinforcing construction consisting of vertically disposed cross ribs 15 and 16, which ribs stop short of the upper edge of a tile to provide a ledge 17. This ledge 17 affords means to receive the plate or cover 5.

The above arrangement and construction of parts forms a very efficient and relatively inexpensive structure which greatly enhances the appearance of a room since the ceiling contour presents a plane surface. The tiles may be manufactured at a plant and shipped to destination ready for installation, and these tiles may be installed by unskilled labor, which is a very desirable feature.

Another advantage resides in the fact that I am enabled to obtain a uniform plastering surface throughout the ceiling. This is because of the fact that the plaster boards provide a plastering surface which is uniform so that stains, as frequently appear upon ceiling surfaces from above, are eliminated.

I am aware that the invention may be embodied in other specific forms without departing from the spirit or essential attributes thereof, and I therefore desire the present embodiment to be considered in all respects as illustrative and not restrictive, reference being had to the appended claims rather than to the foregoing description to indicate the scope of the invention.

What I claim is:

1. A floor structure having completely concealed beams comprising spaced beams, a plurality of hollow tiles arranged between adjacent beams, each tile having a flanged solid base and recessed at its top to receive a cover plate, adjacent bases abutting with the flanged parts of at least some of the tile bases completely covering a beam bottom, the tops of said tiles being substantially flush with the tops of said beams, a cover plate for each hollow tile, and cementitious material arranged between said tiles.

2. A floor structure having completely concealed beams comprising spaced beams, a plurality of hollow tiles arranged between adjacent beams each tile having a flanged solid base and recessed at its top to receive a cover plate, adjacent bases abutting in interlocked relation with the flanged parts of at least some of the tile bases completely covering

a beam bottom, the tops of said tiles being substantially flush with the tops of said beams, a cover plate for each hollow tile, and cementitious material arranged between said tiles.

3. A floor structure having completely concealed beams comprising spaced beams, a plurality of internally reinforced hollow tiles arranged between adjacent beams, each tile having a flanged solid base and recessed at its top to receive a cover plate, adjacent bases abutting with the flanged parts of at least some of the tile bases completely covering a beam bottom, the tops of said tiles being substantially flush with the tops of said beams, a cover plate for each hollow tile, and cementitious material arranged between said tiles.

4. A floor structure having completely concealed beams comprising spaced beams, a plurality of hollow tiles arranged between adjacent beams, each tile having a flanged solid base and recessed at its top to receive a cover plate and vertically disposed portions exteriorly provided with a plurality of ribs, adjacent bases abutting with the flanged parts of at least some of the tile bases completely covering a beam bottom, the tops of said tiles being substantially flush with the tops of said beams, a cover plate for each hollow tile, and cementitious material arranged between said tiles.

5. A floor structure having completely concealed beams comprising spaced beams, a plurality of hollow tiles arranged between adjacent beams, each tile having a flanged solid base and recessed at its top to receive a cover plate, adjacent bases abutting with the flanged parts of at least some of the tile bases completely covering a beam bottom, the tops of said tiles being substantially flush with the tops of said beams, a cover plate for each hollow tile, and cementitious material arranged between said tiles.

6. A floor structure having completely concealed beams comprising spaced beams, a plurality of hollow tiles interiorly provided with cross ribs arranged between adjacent beams, each tile having a flanged solid base and recessed at its top to receive a cover plate, adjacent bases abutting with the flanged parts of at least some of the tile bases completely covering a beam bottom, the tops of said tiles being substantially flush with the tops of said beams, a cover plate for each hollow tile, and cementitious material arranged between said tiles.

FREDERICK M. VENZIE.
